CALIBRATING UNIT FOR INJECTOR TEST STAND

Stanley E. Franklin, Wilmington, Calif., assignor to
Marine Pumps, Inc., Wilmington, Calif., a corporation
of California

Filed May 16, 1957, Ser. No. 46,199

Term of patent 14 years

(Cl. D52—1)

FIG. 1.

Des. 189,059

PAGE 2

Fig. 2.

Des. 189,059

PAGE 3

Fig. 3.

Des. 189,059

PAGE 4

Fig. 4.

Fig. 5.

Figure 1 is a side elevational view of a calibrating unit for injector test stand, showing my new design;

Figure 2 is a front elevation thereof;

Figure 3 is a view in elevation of the side opposite that of Fig. 1;

Figure 4 is a rear view, and

Figure 5 is a top plan view thereof.

I claim:

The ornamental design for a calibrating unit for injector test stand, substantially as shown.
